UNITED STATES PATENT OFFICE.

CHETWOOD SMITH, OF WORCESTER, AND BERTRAM C. HARPER, OF BOSTON, MASSACHUSETTS, ASSIGNORS TO STACK HEATER COMPANY, OF BOSTON, MASSACHUSETTS, A CORPORATION OF MASSACHUSETTS.

INDIRECT WATER-HEATING APPARATUS.

Application filed February 17, 1922. Serial No. 537,276.

To all whom it may concern:

Be it known that we, CHETWOOD SMITH and BERTRAM C. HARPER, citizens of the United States, said SMITH residing at Worcester, in the county of Worcester and State of Massachusetts, said HARPER residing at Boston, county of Suffolk, and State of Massachusetts, have invented a new and useful Indirect Water-Heating Apparatus, 10 of which the following is a specification.

This invention relates to improvements in indirect water heating apparatus such as is used in hot water storage and supply systems. Similar devices now commonly in use are effective for heating the water supply under normal conditions of operation, but having a marked tendency to become overheated at times of reduced demand, particularly if associated with main heaters 20 used for other purposes.

It is the general object of our invention to improve the construction of such heating apparatus, particularly by providing improved devices for preventing or relieving overheating and for maintaining an adequate supply of water in the indirect heating system.

Another object of our invention is to provide for proper disposal of the steam or water, if any is discharged from the indirect system by reason of overheating.

Our invention further relates to arrangements and combinations of parts which will be hereinafter described and more particularly pointed out in the appended claims.

A preferred form of our invention is shown in the drawing which is a front elevation of our improved apparatus, parts thereof being shown in section.

Referring to the drawing, we have shown a hot water storage tank 10 which may be of any usual construction and which is provided with the usual cold water supply pipe 11 and hot water discharge pipe 12. The 40 storage tank 10 is connected by upper and lower pipes 13 and 14 to the opposite ends of a coil or nest of pipes 15 contained within a casing 16 and forming therewith an indirect water heater.

A main heater 20 is shown in the drawings and, in this particular embodiment of our invention, this heater is in the form of a hot air furnace. A heating unit 21 extends into the fire box of the main heater 20

and is connected by upper and lower pipes 55 22 and 23 with the indirect heater casing 16.

A water supply tank 24 is connected by a pipe 25 to the lower connection 23 between the heating unit and the indirect heater. The tank 24 is open to the atmosphere and 60 the water level therein is controlled by a float valve of any usual form.

A vent pipe 26 extends upward from the upper connection 22 and is provided with an outlet 27 controlled by a valve 28. A 65 pipe 29 extends from the pipe 26 to the heater 20 where a branch pipe 30 extends into the ash pit of the heater and is provided with a valve 31. A second branch pipe 70 32 controlled by a valve 34 extends into the water box 33 commonly provided in hot air furnaces for moistening the air passing through the furnace. A safety valve 35 of any usual design is also preferably connected to the pipe 26.

In the operation of our improved water heating apparatus, it is our intention that one or more of the valves 28, 31 and 34 shall be open at all times and the safety valve 35 is required for protection only in the event 75 that all of these valves are accidentally closed at the same time.

Assuming that the valve 28 only is open, the pipe 26 will be filled with water to the level of the water in the supply tank 24, 80 but will permit the discharge of steam from the indirect heating system should the same become overheated. This condition not infrequently arises, particularly in house heating apparatus on occasions when the main 85 heater 20 is being heavily fired while the demand for hot water from the tank 10 is at the same time reduced. Should the water in the indirect system become overheated, the steam is discharged from the outlet 90 27 and any water discharged therewith is 95 immediately replaced from the supply tank 24.

It is sometimes objectionable to discharge this steam and water mixture directly into the atmosphere of the cellar or other space in which the heater is located. To avoid 100 this objection, we have provided the pipe 29 and its branch pipes 30 and 32. When the pipe 30 is open, the steam or water from 105 the vent pipe 26 is discharged into the ash pit of the heater. The steam passes upward through the fuel bed and may be of actual

advantage in the process of combustion. If the steam and water is discharged through the pipe 32 into the water box 33, the temperature of the water is raised and the amount of water vapor supplied to the air is increased, which is also a desirable attainment.

While we have shown in the drawing a system in which all three of these relief connections are provided, in actual use it will be usually found that a single selected connection is sufficient in which case no shut-off valve or safety valve is necessary.

Certain of the advantages of our invention may be obtained by the use of the supply tank 24 and its connecting pipe 25 only, omitting the vent pipe 26. In this case, the excess of pressure caused by the overheating of the unit 21 is to some extent relieved through the pipe 25. Satisfactory operation is, however, much improved by the addition of the vent pipe 26 connecting into the upper pipe 22.

Having thus described our invention, it will be evident that changes and modifications can be made therein by those skilled

in the art within the spirit and scope of our invention as set forth in the claims, and we do not wish to be otherwise limited to the details herein disclosed but what we claim is:

1. Water heating apparatus comprising a storage tank, an indirect water heater therefor, a main heater, a heating unit therein, upper and lower connections forming with said indirect heater and said unit an indirect heating system, a water supply, and a vent pipe for said system discharging into the ash pit of said main heater.

2. Water heating apparatus comprising a storage tank, an indirect water heater therefor, a main heater having a water box, a heating unit in said main heater, connections forming with said indirect heater and said heating unit an indirect heating system, and a vent pipe for said system, said vent pipe discharging into said water box.

In testimony whereof we have hereunto affixed our signatures.

CHETWOOD SMITH.
BERTRAM C. HARPER.
